UNITED STATES PATENT OFFICE.

JOSEPH RALPH TRETHEWEY, OF KIMBERLEY, BRITISH COLUMBIA, CANADA.

GARMENT HANGER.

Application filed May 15, 1928. Serial No. 109,315.

My present invention relates to improvements in a garment hanger appertaining particularly to a rack for holding hats, coats, cloaks, umbrellas and the like adapted to be applied to the back of a pew, opera seat or other vertical surface.

An object is to provide a garment support of this kind that is collapsible to occupy a minimum of space when not in use and yet adequately accommodate one's heavy outer wraps, such as a coat or cloak and hat.

A further object is to provide such a device that will support the garments in close proximity to the vertical surface to which it is applied without creasing or otherwise damaging the same, that will readily receive the several articles of apparel designed to be supported thereby, and from which such garments may be conveniently removed.

20 A still further object is the provision of such a device wherein the number of parts are few, the construction simple and the cost of production low, the whole being rendered commercially desirable.

25 To the accomplishment of these and related objects as may become apparent, my invention resides in the construction, combination and arrangement of parts as shall be hereinafter more fully described illustrated in the accompanying drawings and pointed out in the claims hereunto appended.

30 So that the device may be best understood and more readily described, attached drawings of a possible mechanical expression are 35 to be considered as forming a part of this disclosure and in these

Fig. 1 is a perspective view of a preferred embodiment, the same being shown in operative position; and

40 Fig. 2 is an elevation thereof in closed position, part of the body being broken away.

Referring particularly to these drawings wherein like characters indicate like parts throughout the several views, the numeral 3 indicates a frame.

45 This frame will preferably be stamped from sheet metal and formed as a shallow channel 4 having an extension 5 of the base continuing at one side and doubled back on itself, the arms of the channel being terminally flanged outwardly, as at 6, to provide fastening ribs by which said hanger may be applied to any desired vertical surface having the channel disposed horizontally and the base continuation thereof on the upper

side. An elongated slot 8 is cut in the base of the channel extending in width upwardly from flush with the lower edge or arm of the channel 4. The shelf thus formed is indented near an end as at 9 for a purpose to be hereinafter described.

50 A prop arm 10 is normally received in the groove, formed by and disposed between the upwardly extending base extension 5 and the upper arm flange 6 of the channel 4; one end thereof being hingedly connected as at 11 to a vertical pivotal post 12 journalled in the arms of the channel 4. This prop arm 10 hinging vertically in the post 12 may 55 pivot to one side thereon to lie horizontally in the frame groove and through an angle of something less than 180° to stop and be supported at an incline on the other side of said post. A notch 13 is cut in the extension 5 in registry with said post 12 to accommodate this prop when the same is hinged to the side of the post designed to support it at an incline and the said post is turned 60 through a right angle so that the said arm 10 extends outwardly from the hanger supporting surface.

65 A pair of spaced arms pivoted between the arms of the channel 4 are designed to hinge horizontally outwardly through the elongated slot 8 into operative position. One of these arms is pivoted near an end of this slot so that when hinged perpendicularly to the vertical surface it engages and is stopped by the adjacent end of the slot 8. A bar 16 70 is hinged to the free end of this arm 15 having a free end 17 adapted to engage and be removably supported by the free end of the remote and second arm 15, an arcuate bifurcated tongue 18 being formed terminally on 75 this second arm 15 to receive the free end 17 of the bar 16 which is provided with registering arcuate grooves 19 on both the upper and lower sides. Near their adjoining ends, both the bar 16 and the second of the arms 100 15 have small depending knobs 20. When closed, the arms 15 and bar 16 are housed within the channel 4, entering through the slot 8, in this position the knobs 20 are accommodated by the notch 9 and are consequently available and conveniently disposed 105 when it is desired to open this hanger into operative position.

To maintain the bar 16 in its normally closed position in the slot 8, I provide a 110 spring fastening ring 21 having an open side facing outwardly, the ends 22 of the

ring, at the opening, being doubled back on themselves and bent into alignment in opposite directions, passing through the spaced arms of the channel 4. The ring thus presents to the slot opening a pair of spaced spring jaws adapted to receive the bar 16, for fastening purposes, when closed.

The structure of the device being described in detail, the modus operandi thereof is now set forth:—In closed and inoperative position, the prop arm disposed horizontally lies compactly and out of the way in the base extension and flange formed groove while the hinged arms and the bar supported thereby are all hinged into the channel through the elongated slot, the depending knobs extending through the notch being alone exposed. In use, the prop arm is hinged in its post through the entire available angle of between 90° and 180° and the post simultaneously pivoted at right angles so that the prop arm extends outwardly and upwardly as a supporting finger to receive a hat and scarf or the like, the same being disposed in the notch in the base extension there located to receive said arm. The bar on its hinged arm and the free arm are then hinged outwardly, disconnectedly, and the former is ready to receive a coat, cloak or other heavy outer wrap and following the placement and reception thereof is hinged to engage the bifurcated end of the free knob-carrying arm, in which position it is supported horizontally, parallel with the frame and in close proximity to the same. Thus the outer and removable wraps are conveniently and compactly supported without injury to the garments and in a way that does not require space ordinarily used or encroach on the comfort or freedom of the person.

From the foregoing description taken in connection with the accompanying drawings, it will be manifest that a garment hanger is provided which will fulfill all the necessary requirements of such a device, but as many changes could be made in the above description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

What I claim as new and desire to secure by Letters Patent is:—

1. A garment hanger comprising a frame stamped from sheet metal formed as a shallow channel having the arms thereof flanged outwardly to provide fastening ribs adapted to be applied laterally to a vertical supporting surface, the base of said channel being extended upwardly and doubled back on itself to form a ridge parallel with and

spaced from the flanged end of the adjoining arm of the channel and a garment supporting arm normally seating therein.

2. A garment hanger comprising a frame stamped from sheet metal formed as a shallow channel having the arms thereof flanged outwardly to provide fastening ribs adapted to be applied laterally to a vertical supporting surface, the base of said channel being extended upwardly and doubled back on itself to form a ridge parallel with and spaced from the flanged end of the adjoining arm of the channel and a garment supporting arm hinging vertically in an upright pivoted post normally seating therein.

3. A garment hanger comprising a frame stamped from sheet metal formed as a shallow channel having the arms thereof flanged outwardly to provide fastening ribs adapted to be applied laterally to a vertical supporting surface, the base of said channel being extended upwardly and doubled back on itself to form a ridge parallel with and spaced from the flanged end of the adjoining arm of the channel; an elongated slot in the base of said channel; a collapsible garment rack normally housed within said channel adapted to be extended into operative position through said slot; a vertical and pivoted post journaled in the arms of said channel centrally of the ends of said frame and an arm hinging vertically therein normally seating in the groove formed by said spaced ridge and parallel flanged end and adapted in operative position to extend upwardly and outwardly from said frame.

4. A garment hanger comprising a frame stamped from sheet metal formed as a shallow channel having the arms thereof flanged outwardly to provide fastening ribs adapted to be applied laterally to a vertical supporting surface, the base of said channel being extended upwardly and doubled back on itself to form a ridge parallel with and spaced from the flanged end of the adjoining arm of the channel; an elongated slot in the base of said channel lying along the lower side thereof; a pair of spaced arms hinged horizontally in said frame between the arms thereof, a coat carrying bar hinged at one end to the other end of one of said arms and removably connected at the remote end to the free end of the second of said arms adapted to be extended into operative position through said slot; a vertical and pivoted post journaled in the arms of said channel centrally of the ends of said frame and an arm hinging vertically therein normally seating in the groove formed by said spaced ridge and parallel flanged end and adapted in operative position to extend upwardly and outwardly from said frame.

In testimony whereof I hereunto affix my signature.

JOSEPH RALPH TRETHEWEY.
